US0D1020629S

(12) **United States Design Patent** (10) **Patent No.:** **US D1,020,629 S**
(45) **Date of Patent:** **** Apr. 2, 2024**

(54) **PORTABLE ELECTRONIC DEVICE CHARGER**

(71) Applicant: **Pioneer Square Brands, Inc.**, High Point, NC (US)

(72) Inventor: **William Miles Haskins**, Kernersville, NC (US)

(73) Assignee: **Pioneer Square Brands, Inc.**, High Point, NC (US)

(**) Term: **15 Years**

(21) Appl. No.: **29/916,446**

(22) Filed: **Nov. 10, 2023**

(51) **LOC (14) Cl.** **13-02**

(52) **U.S. Cl.**

USPC **D13/108**

(57) **CLAIM**

The ornamental design for a portable electronic device charger, as shown and described.

DESCRIPTION

FIG. 1 is a front perspective view of a portable electronic device charger showing my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left elevational view thereof; and,

FIG. 7 is a right elevational view thereof.

The broken lines in the drawing figures depict portions of the portable electronic device charger that form no part of the claimed design.

1 Claim, 5 Drawing Sheets
